METHOD AND MEANS FOR CONTROLLING
THE IONIC CONTENT OF AIRConstantin P. Yaglou, Boston, Mass., assignor, by
mesne assignments, to Carrier Engineering
Corporation, Newark, N. J., a corporation of
New York

Application May 4, 1933, Serial No. 669,362

9 Claims. (Cl. 204—32)

This invention relates to the conditioning of air, more particularly to the control of the ionic content thereof, and is, in part, a continuation and improvement of my invention as described in 5 copending application Serial No. 587,960, filed January 21, 1932.

The invention is directed primarily to the production of ions of desired electrical character and mass and in prescribed quantities numerically. 10

As was pointed out in my said previous disclosure, present general air conditioning practice attempts to condition a given atmosphere by controlling such factors as temperature, humidity, 15 and air motion. The control of these factors, while promoting a much improved condition of comfort, still leaves one important factor unaccounted for, namely, ionic content. While the air may be at exactly the correct temperature, 20 have exactly the correct dewpoint, and may be perfectly distributed, it still may not have the "freshness" that is so apparent, for example, at the seashore or in the mountains. Such apparent lack of "freshness" in the air may be 25 traced directly to the reduced number or absence of ions in the air.

Air, as any other gas, may be ionized. Ions 30 may be classified as to sign, either positive or negative, and also, as to size, either small, large or intermediate. Physically, and from a physiological standpoint, the small ions appear to be the most important. Large ions are as a rule associated with aerial pollution; the greater the pollution, the greater the concentration of large 35 ions.

Although the production of small ions is continually carried on in nature by solar radiation, cosmic rays, radioactive disintegration and as a result of other phenomena, many adverse forces 40 tend to destroy these ions. For example, ions of opposite sign tend to agglomerate and in the process neutralize themselves. Similarly, in dusty air, small ions agglomerate, with dust particles or condensation nuclei forming large ions. Also, 45 they may be destroyed by grounding and in a number of other ways encountered naturally in the atmosphere. Further, under different climatic conditions, ions vary widely not only as to number, but in respect of sign and size.

Experiment has demonstrated that the ionic 50 content of enclosed atmospheres, as in theatres, auditoria, or other inhabited areas, varies not only with changes in climatic conditions, but that human or animal occupancy tends to destroy 55 ions at a high rate. Thus, the artificial produc-

tion of ions to make up deficiencies in ionic content and the control of such production to assure ions of desired character and number becomes of major consequence. 5

The general object of the invention is to provide an improved method and means for producing ions of desired character, as to sign and size, substantially in unlimited quantities for practical purposes in controlling the ionic content of enclosures. 10

A further object is to produce ions of suitable character, in desired quantities, without the production of ozone.

Another object is to provide ions of desired character and number without setting up electrical disturbances apt to interfere with radio reception. 15

A feature of the invention resides in the use of a step-up transformer in combination with a rectifying device to give a source of high potential uni-directional current. 20

When utilizing direct or uni-directional current to produce ions, I have found that substantial ionization begins when the potential on the ionizing head is about 8,500 volts. Above 25 10,000 volts, the production of ions is apparently directly proportional to the potential. Another feature of the invention utilizes this discovery and resides in a simple provision of transforming means suitably arranged for varying the voltage quantitatively and hence, the ionic output. Other means in combination therewith are arranged to control the sign, as well as the proportions of positive to negative ions. 30

Another feature of the invention resides in 35 utilizing a condenser in the electrical circuit in such manner that the peaks and variations in the ionizing potential are smoothed out. As a result, the production of ions is considerably increased, and the consumption of electrical energy 40 is correspondingly reduced.

A further feature of the invention resides in substantially eliminating corona, or any other form of brush or arc discharge, as well as eliminating the employment of spark gaps, in the production of ions. 45

Another feature resides in the provision of a grounded cylindrical grid, or a plane metal shield in combination with a circuit having two ionizing 50 heads, adapted to produce both positive and negative ions. By varying the diameter of the grid surrounding one of the ionizing heads or by adjusting the plane metal shield with respect to the ionizing heads, a preponderance, in any proportion- 55

ions, either of positive or negative ions, may be produced.

Other objects and features covering constructional and engineering advantages making for simplicity, efficiency and preclusion of ozone will be more apparent from the following description and drawings, in which:

Fig. 1 is a diagrammatic view, partly in section, of an air conditioning system to which the invention may be applied;

Fig. 2 represents an electrical circuit arrangement adapted to carry out the invention;

Fig. 3 represents a modification of the electrical circuit of Fig. 2;

Fig. 4 is a simplified electrical circuit adapted to carry out certain objects of the invention;

Fig. 5 and 5a are modifications of the circuit arrangement of Fig. 4 and they are particularly adapted to the production of negative ions exclusively;

Figs. 6 and 6a represent simplified electrical circuit arrangements adapted to produce positive ions exclusively; and

Figs. 7 and 7a represent electrical circuits by means of which both positive and negative ions, in a desired ratio, may be produced.

Considering the drawings, similar designations referring to similar parts, and first referring to Fig. 2, numeral 5 designates a step-up transformer having a primary winding 6 and a secondary winding 7. Alternating current, from my available source, is suitably connected to the primary winding 6 through leads 8 and 9. A variable resistance 10, in the lead 9, is adapted to vary the voltage impressed on the primary winding 6, and a fuse 11, in the lead 8 affords protection to the transformer, and other parts of the apparatus, against accidental overload. Although resistance is shown in the primary circuit, it is to be understood that any other expedient such as an inductive reactance or a tapped secondary might be employed.

A rectifying device is provided in the circuit to change the character of the current supplied by the secondary winding 7 from alternating to uni-directional. Although the rectifier may be one of many types and may operate on one of many principles, applicant illustrates a simple, efficient and inexpensive device comprising an evacuated tube 12 in which are suitably mounted a filament 13 and a plate element 14. While one large tube is shown, several smaller tubes may be used in series to secure the desired voltage. For the purpose of heating the filament, a small step-down transformer 15 has its primary winding 16 suitably connected, as by leads 18 and 19, across leads 8 and 9 and in series with the resistance 10 and fuse 11. The secondary winding 17 is connected to the filament 13. Lead 20, from secondary winding 7 of transformer 5, is connected to the filament 13, and under certain conditions which will be made apparent hereinafter, the other lead 21 is grounded as at 24. The plate 4 is connected by a well insulated lead 22 to an ionizing head 23, and a condenser 25, of suitable capacity and proper dielectric strength, is located between the plate circuit and lead 21. While the condenser is not absolutely essential, the marked increase in efficiency of the apparatus when it is used makes it desirable, particularly in units of very high ionizing capacity.

The head 23, which in practice may be mounted within duct 26 (Fig. 1) preferably comprises a brass ball, or the like, about three quarters to one

and a half inches in diameter. Sharp projections, such as, for example, phonograph needles, are tapped into the ball. When a high electrical potential is impressed on the head 23, these needles produce a very powerful electrical field all around the head, hence, ionizing any gas coming into the sphere of influence of said field. 5

Under conditions which make it desirable to produce negative ions exclusively, the circuit arrangement may be precisely as shown in Fig. 2. 10 If, on the other hand, all positive ions are desirable, the ionizing head 23 will be connected to lead 21 and the plate of the rectifying tube will be grounded. In other words, the ground and ionizing head will be in reverse position to that 15 shown in Fig. 2. Primarily then, the apparatus of Fig. 2 is adapted to produce ions of either positive or negative character.

In Fig. 3, the ground 24 of Fig. 2 has been replaced by a second ionizing head 27, similar in all respects to head 23. A shield 28, comprising a metal strip or plate, is adjustably positioned between the heads 23 and 27 and is grounded as at 29. Except for these changes, the apparatus and circuit of Fig. 3 may be identical with that of Fig. 2. In operation, the device of Fig. 3 is capable of producing both positive and negative ions. By moving the shield 28 with respect to heads 23 and 27, a preponderance of ions having a desired characteristic may be established. For example, if the shield is moved closer to 23 than to 27, a preponderance of positive ions will result, while if the shield is moved into proximity with head 27, a preponderance of negative ions will be established. In this manner, any desired ratio 35 of positive to negative ions may be obtained. While the shield is illustrated as a plate 28, in practice it is desirable to use grounded cylindrical grids surrounding the ionizing heads. The grids are preferably constructed in such a manner that their diameter may be varied, i. e., increased or decreased. By varying the diameter, the distance between the head and the grid may be varied to give the effect achieved by moving the shield 28 of Fig. 3 closer to one of the ionizing heads. By varying the resistance 10, the potential impressed on the ionizing heads may be varied, and as has been found, the number of ions produced by an apparatus such as is illustrated in Figs. 2 and 3 is directly proportional to the 50 potential (above 10,000 v.); hence, the number of ions produced may be controlled.

For most practical purposes, particularly those wherein the desired concentration is less than 20,000 ions per cubic centimeter of room air, the 55 rectifying tube 12, its filament transformer 15, and condenser 25 may be dispensed with. The resulting circuit, with various modifications, is shown in Figs. 4, 5, 5a, 6, 6a, 7, and 7a.

Figs. 4, 5 and 5a show various circuits adapted to the production of negative ions exclusively, and comprise generally a light duty transformer 5, a rheostat 10 in series with primary winding 6, and two ionizing heads 23 and 27 arranged in the secondary circuit. As can be seen from the drawings, the main difference between these circuits lies in the particular arrangement of the ionizing heads in the secondary circuit, and in the method of grounding, i. e., in Fig. 4, the heads 23 and 27 are connected to opposite terminals of secondary winding 7, and no ground connection is provided; in Fig. 5, the ionizing heads are arranged as in Fig. 4, but the midpoint of secondary winding 7 is grounded to the trans- 75

former casing as indicated at 44; and in Fig. 5a, the ionizing heads are connected in parallel with one terminal of secondary winding 7, the other terminal being grounded as at 45.

Figs. 6 and 6a are circuits, particularly adapted to the production of positive ions exclusively. In these figures, the heads 23 and 27 are connected to the opposite terminals of secondary winding 7 of transformer 5. In Fig. 6, the midpoint of the secondary is grounded to the transformer casing, as indicated at 44. In both circuits, a cylindrical grid 47 surrounds one of the ionizing heads, but is separated therefrom by an air space sufficiently wide to prevent disruptive or corona discharge therebetween. The grid is grounded as at 45. While a grid has been found most efficient, comparable results can be secured by placing a grounded metal shield (of the type illustrated in Fig. 3) near one ionizing head.

Figs. 7 and 7a show circuits adapted to produce both positive and negative ions in desired proportions. In Fig. 7, the midpoint of secondary winding is grounded to the transformer casing as indicated at 44, and the ionizing heads 23 and 27 are connected to opposite terminals thereof. Each head is provided with a cylindrical grid 47, preferably constructed so that the diameter of the grid may be varied. The grids are grounded as at 45. The diameter of the grids are adjusted at a desired minimum to provide an air space which will prevent corona or disruptive discharge at the particular voltage used. If one grid is then increased from this minimum diameter, a preponderance of positive ions will be produced, while increasing the diameter of both grids results in the production of a preponderance of negative ions.

In applying the invention to an air conditioning system, as illustrated, for example, in Fig. 1, the ionizing head 23, or heads 23 and 27, may be mounted in the duct 26 and suitably insulated therefrom as by insulator 43.

The air conditioning system (Fig. 1) comprises a conditioner 30, equipped with sprays 31, fed with water, or other liquid, at desired temperatures from a refrigerating machine 32 by a pump 33. A mixing valve 34, operative responsive to thermostat 35 in the conditioner, is adapted to control the temperature of the sprays, hence, the dewpoint in the conditioner.

Outside air, through the inlet controlled by dampers 36, and air returned from the enclosure 37 through duct 38 and damper 39, is passed through the conditioner 30 in desired proportions. Subsequent to conditioning this mixture may be augmented and attemperated by a volume of return air through dampers 39 and delivered by fan 40 through supply duct 26 to the enclosure 37. The proportions of fresh and return air are varied and controlled by the operation of thermostat 35, while the amount of bypassed air utilized is controlled by a thermostat 41 located in the return duct 38. A reheater 42, of any suitable type, serves to heat the air, under winter conditions, prior to its delivery to the enclosure, the amount of heating done being regulated by thermostat 41. The ionic content, as to number and character of ions will be controlled by regulating the production at the head or heads in duct 26, as may be required, and in accordance with any of the circuit arrangements described.

While applicant has illustrated his invention, in connection with Fig. 2, for example, as using rectified alternating current, he does not limit

himself to this precise means, but may use instead a motor generator or source of high potential uni-directional current.

Since certain changes in carrying out the above process and in the constructions set forth which embody the invention may be made without departing from its scope, it is intended that all matter contained in the above description or shown in the accompanying drawings shall be interpreted as illustrative and not in a limiting sense.

I claim as my invention:

1. The method of producing positive and negative ions in respiratory air which comprises utilizing a source of high potential uni-directional current, feeding said current to a plurality of shielded leak devices to produce a high intensity electrical field, passing respiratory air through said field whereby it will be ionized, and varying the position of the shielding with respect to said leak devices to vary the relative proportions of positive and negative ions produced in said air.

2. The method of ionizing a fluid, consisting in utilizing a high potential, uni-directional current to produce a pair of electrical fields, shielding one of said fields from the other, varying the position of said shielding with respect to said fields to vary the proportions of positive and negative ions produced in a fluid subjected to said fields, and varying the ionizing capacity of said fields by varying the potential of said current.

3. A combination of apparatus for producing positive and negative ions, comprising a pair of pointed electrodes, means for establishing a potential difference between said electrodes, a grounded shielding means positioned therebetween, said means being movable with respect to said electrodes, whereby the proportions of positive and negative ions produced by said electrodes will be varied.

4. A method of producing positive and negative ions in respiratory air which comprises utilizing a source of high potential current, establishing an electrical potential between a plurality of pointed electrodes to produce a high intensity electrical field about said electrodes, passing respiratory air through said field whereby it will be ionized, and shielding one of said electrodes with a grounded shield, other of said electrodes remaining unshielded whereby positive and negative ions in desired ratio are produced, substantially free of ozone.

5. A method of producing ions substantially free from ozone, in respiratory air, which comprises utilizing a source of high potential current, feeding said current to a pointed electrode connected to one terminal of said source, to produce a high intensity electrical field about said electrode, passing respiratory air through said field whereby it will be ionized and connecting the other terminal of said source to another pointed electrode, the intensity of the electrical field between said electrodes being below that required to cause substantial discharge between them.

6. A method of producing ions, substantially free from ozone, in respiratory air, which comprises utilizing a source of high potential current, feeding said current to a pointed electrode connected to one terminal of said source to produce a high intensity electrical field about said electrode, passing respiratory air through said field whereby it will be ionized, connecting the other terminal of said source to another pointed elec-

trode, and establishing an electrical field between one of the electrodes and a grounded shield, the other of the electrodes remaining unshielded.

5. 7. A method of producing ions, substantially free from ozone, in respiratory air, which comprises utilizing a source of high potential current, feeding said current to a plurality of pointed electrodes connected to both terminals of said source to produce a high intensity electrical field about said electrodes, passing respiratory air through said field, whereby it will be ionized, and shielding only one of said electrodes whereby positive and negative ions will be produced by said electrodes in desired ratio.

10. 8. A combination of apparatus for producing ions, substantially free from ozone, in respiratory air, comprising a source of high potential current, a first pointed electrode connected to a first terminal of said source, a second pointed electrode connected to a second terminal of said source, and a grounded shielding means positioned adjacent one of said electrodes, said shielding means being a substantial distance from said

second electrode whereby positive and negative ions will be produced by said electrodes in desired ratio and whereby no substantial discharge occurs between said second electrode and said shielding means.

9. A method of producing ions, substantially free from ozone, in respiratory air, which comprises utilizing a source of high potential current of the order of 8500 volts and greater, feeding said current to a needle pointed electrode connected to a selected terminal of said source to produce a high intensity electrical field about said electrode without producing ozone, passing respiratory air through said field whereby it will be ionized and connecting the other terminal of said source to ground, whereby ions substantially exclusively of the selected polarity will be produced, the sharpness of the pointed electrode being sufficient to prevent the formation of ozone, the intensity of the electrical field between the electrode and ground being below that required to cause substantial discharge between them.

CONSTANTIN P. YAGLOU.
